NECKTIE CONSTRUCTION

Lucilla de Vescovi Whitman, New York, N. Y.

Application February 29, 1944, Serial No. 524,351

1. Claim. (Cl. 2—146)

1 This invention relates to neckties and more particularly to novel constructions whereby a necktie incorporating the invention may be tied so as to present any one of two or more possible surface patterns, as may be selected by the wearer.

It is an object of the invention to provide a necktie which may be worn with either of its sides in front and wherein the structure of the tie is such that in use it gives substantially the same appearance as a conventional necktie. Another object of the invention is to provide a tie of a tubular sort wherein the longitudinal folds forming the side edges of the tie may be located in the tie at the option of the wearer. A still further object of the invention is the provision of a necktie capable of presenting a number of different surface configurations. Other objects will be in part pointed out as the description proceeds and will in part become apparent therefrom.

The invention, accordingly, consists in the features of construction, combinations of elements, and arrangements of parts as will be set forth in the accompanying specification and the scope of the application of which will be indicated in the accompanying claim.

In the drawings:

Figure 1 is a plan view with parts broken away of a necktie embodying one form of the invention;

Figure 2 is a plan view of a blank pattern used in forming the necktie illustrated in Figure 1;

Figure 3 is a sectional elevation on an enlarged scale taken along the line 3—3 of Figure 1 in the direction of the arrows;

Figure 4 is a view similar to Figure 1 showing a modified construction in accordance with the invention;

Figure 5 is a view similar to that of Figure 2 but illustrating a pattern used in making the tie of Figure 4;

Figures 6 and 7 are sectional elevations on an enlarged scale taken along the lines 6—6 and 7—7, respectively, of Figure 4 in the direction of the arrows;

Figure 8 is a plan view similar to that of Figure 1 but showing a further embodiment of the invention;

Figure 9 is a second plan view of the tie illustrated in Figure 8 indicating an alternative manner in which the tie may be used;

Figure 10 is an end elevation on an enlarged scale taken along the line 10—10 of Figure 8 in the direction of the arrows;

2

Figure 11 is a sectional elevation on an enlarged scale taken along the line 11—11 of Figure 8 in the direction of the arrows; and

Figure 12 is a sectional elevation on an enlarged scale taken along the line 12—12 of Figure 9 in the direction of the arrows.

The accompanying drawings illustrate, by way of example, three forms which the present invention may take. It has heretofore been discovered that neckties may be fashioned from two dissimilar pieces of material so that either side of the tie may be placed on top before tying, whereby the tie serves a dual capacity of presenting either of its surfaces. Such neckties have been of conventional size and shape, the two tie pieces simply being sewed together by a seam running around the outer edge of the tie. These neckties have suffered the disadvantage of having an unattractive seam portion adjacent the longitudinal edges of the tie. This was true no matter how fine the seam might be nor how nicely it was positioned at the exact edge of the tie.

The present invention provides a tie which, in two of the embodiments illustrated, incorporates a recessed and hidden seam in connection with the edges of the front portion of the necktie. This hidden seam is made possible by a pleat construction as will be described more fully hereinafter.

In an alternate embodiment of the invention, a novel end seam construction is effected whereby the longitudinal seams between the two tie surface pieces may be located, at the will of the wearer, either at the edges of the tie or at some intermediate portion of the tie so that the tie may be worn not only to give two unbroken surfaces, but also, by locating a seam intermediate of the longitudinal edge portions, the tie may be used to combine selected portions from each of the two tie surface pieces, all as will be described more fully in the following specification.

Figure 1 illustrates a necktie 20 having a broad end 22, a relatively narrower end 24 and an intermediate neck portion 26. The tie comprises a first tie surface piece 28 (on top as viewed in Figure 1) and a second tie surface piece 30 shown at the lower portion of the necktie where the first piece is broken away and also shown at the narrow end of the tie where it is turned over. In Figure 2 a blank 32 is indicated such as is used in forming tie 20 of Figure 1. Fold lines 34 are illustrated by dot and dash lines upon the blank, and it will be seen at the broader portion of the tie that fold portions 36 are de-

lineated by fold lines 34. When two blanks 32 of different materials are cut and folded as indicated in Figure 2, they may be arranged in back to back relationship to form a tie such as is illustrated in Figure 1, wherein a seam 38 extends substantially completely around the tie, and wherein a seam 38 is recessed at the broad end of the tie by virtue of fold portions 36 (see also Figure 3) to effect a pleat 40 on each side edge of the tie. Pleat 40 has the capacity of enhancing the appearance of the tie notwithstanding the fact that the tie includes a complete, hidden tie surface piece beneath the tie surface piece which shows.

Figures 4-7 present a modification of the tie illustrated in Figures 1-3. Similar parts are indicated by corresponding reference characters but with the addition to the reference characters of an "a." This modified necktie is characterized by the fact that its pleat 40a extends upwardly from the bottom of the broad end, as illustrated in Figure 4, only to a limited point, at which point seam 38a assumes a more conventional position adjacent the extreme outer edges of the tie. The type of tie illustrated in Figures 4-7 has advantage in some instances, depending somewhat upon the types of fabrics used, in that pleat 40a stops immediately below the portion which is used in forming the knot when the tie is tied. And thus, any possible interference from pleat 40a during the tying operation is eliminated.

Figures 8-11 illustrate a further embodiment of the invention wherein similar reference characters indicate corresponding parts found in the embodiment of Figures 1-3 but with the addition of a "b." The necktie has a tubular-like property extending from one end to the other. For example, at neck portion 26b the two tie surface pieces are not sewed to one another other than by means of seam 38b. In addition, each end of the tie is characterized by the fact

that it includes an end seam 42b. Seams 42b are essentially nothing more than turned-in edges. This construction departs from the construction illustrated in the preceding embodiments in that tie surface piece 28b is not sewed at the ends to tie surface piece 30b, but rather the tie is left open at each end (see Figure 10). Thus, the longitudinal folds may be impressed into the tie with the longitudinal seams of the two tie surface pieces either at the two longitudinal edges, as illustrated in Figure 8, or centrally located between the two edges, as illustrated in Figure 9, or bearing some other relationship with respect to the sides of the tie. Hence the tie may be used to present a variety of configurations under the control of the wearer.

It is to be kept in mind that the drawings herein are purely by way of exemplification and as such are necessarily more or less diagrammatic. As several additional embodiments may be made of the above invention without departing from the scope thereof, it is to be understood that all matter herein set forth or shown in the accompanying drawings is to be interpreted as illustrative and not in a limiting sense.

I claim:

A four-in-hand necktie of the character described comprising dissimilarly surfaced pieces of necktie material secured together along their edges to form a tube-like necktie of conventional length and width, said tube-like necktie being left open at each end whereby the tie may be flattened along any two opposing longitudinally running fold lines, and each open end being formed by a finished edge which runs endlessly therearound approximately perpendicular to the lengthwise direction of the necktie whereby the ends of the necktie present a neat appearance irrespective of the location of the longitudinally running fold lines.
